SPINNING TOY

Harry A. Tomarin, Cincinnati, Ohio

Application September 4, 1947, Serial No. 141,212

Term of patent 14 years

(Cl. D34—15)

To all whom it may concern:

Be it known that I, Harry A. Tomarin, a citizen of the United States, residing at Cincinnati, in the county of Hamilton and State of Ohio, have invented a new, original, and ornamental Design for Spinning Toys, of which the following is a specification, reference being had to the accompanying drawings, forming part thereof.

Fig. 1 is a side elevational view of the spinning toy, showing my new design.

Fig. 2 is a top view of the spinning toy of Fig. 1.

Fig. 3 is an end view of the spinning toy of Fig. 1.

I claim:

The ornamental design for a spinning toy, as shown.

HARRY A. TOMARIN.
